UNITED STATES PATENT OFFICE.

ARTHUR W. MUSSelman, OF DENVER, COLORADO.

AUTOMATIC RAILWAY GATE.

Application filed March 2, 1926. Serial No. 91,719.

This invention relates to electric systems for the automatic operation of gates at railway crossings, and its primary object is to provide in association with an electric motor for the operation of a railway gate, a system of electrical connections and controlling devices operatively arranged to cause the gate to be closed by a train approaching the crossing and to be reopened after the train has passed the same.

A further object of the invention is to provide in an electric system of the above described character, means to maintain the gate in its closed position after its motor has been actuated by a passing train, in the event of other trains approaching or passing the crossing during the period between the closing and opening movements of the gate.

Another object of the invention is to provide in connection with the gate-operating system, a signal appliance by which the engineer of a train moving or standing adjacent the railway crossing is apprised of the position of the gate and the working condition of the system, and still further objects reside in details of construction and novel arrangement and combinations of parts to be hereinafter fully described with reference to the accompanying drawings.

In the drawings in which like characters of reference designate corresponding parts throughout the several views—

Figure 1 represents, diagrammatically, the system at the time the gate is being closed by an approaching train.

Figure 2, a similar view with the parts in the position during the time of reopening the gate after the train has passed the crossing.

Figure 3, a sectional elevation of a gate adapted for use in the system.

Figure 4, a fragmentary elevation of the rear end of a locomotive inside the cab thereof showing the arrangement of the contact and signal devices included in the system; and

Figure 5, a fragmentary side elevation of the locomotive.

Referring further to the drawings the system as illustrated in Figures 1 and 2, is shown in its simplest form for the operation of a single gate at a road-crossing of a single-track railway. The illustration thus simplified, is thought to be sufficient to convey a complete understanding of the construction, arrangement and operation of the

essential elements of the invention, and it is to be understood that, in practise, two gates at opposite sides of the railway are simultaneously operated; and that by simple electrical interconnections, the system may be extended to be operated by trains moving on two or more railway tracks past the crossings at which the gates are installed.

The gate shown in detail in Figure 3 of the drawing is of the pivoted type. It consists of stand 5 on which is pivoted as at 6, a balanced weighted bar 7 adapted to extend in its lowered position across a highway at a railroad crossing.

The stand is enclosed in a casing 8 which contains in addition to an electric motor 9, the various circuit-controlling devices hereinafter to be described, and the operative connection between the motor and the gate is established by a worm 10 on the rotor of the motor, meshing with a worm gear 12 of larger diameter, on the pivoted gate.

The gate as shown represents a simple and practical embodiment of the element of the invention which is actuated in the operation of the system, to obstruct the highway at the crossing upon the approach of a train, but it is to be understood that gates of different construction, as for example, gates sliding horizontally to and from the obstructive position, may be employed without departing from the spirit of the invention.

The circuit-closing appliances, contact-devices and other parts included in the electrical system, have also been shown in their simplest and, as it appears at the present time, most practical form and it will be further understood that these parts are likewise susceptible to changes within the scope of the invention as will be fully defined in the following part of the description and in the thereunto appended claims.

The reference numeral 13 designates the highway crossing the railway track 16 the approach to which from both directions is to be obstructed by the gates in the operation of the system.

The locomotives of the trains moving on the railway are equipped with contact-devices 14 of either the trolley or pantograph type, adapted to electrically engage with overhead contact rails suspended above the track at opposite sides of the crossing.

But one contact-device is required in the operation of the system but it is desirable that the locomotive be equipped with two

similar contact devices at opposite sides, to permit of its use in the system while moving backward as well as when it moves, as ordinarily, in a forward direction.

5 The overhead contact rails are disposed at opposite sides of the crossing to be successively engaged by the correspondingly positioned trolley or pantograph on the passing train and in order to provide for the operation of the system by trains moving in opposite directions, two pairs of the contact rails are placed at opposite sides of the track at each crossing as shown in the drawings.

15 The contact rails designated by the reference numeral 15, function in the operation to close the gate by trains approaching the crossing and those designated by the numeral 17, are subsequently engaged by the contacts on the trains to re-open the gates.

20 The electric current required in the operation of the system is obtained from a source of electricity on the locomotives of the trains, it being most practical to employ for this purpose, the generators found on 25 all modern engines to provide current for the lighting systems of the locomotives.

30 The source of electricity indicated at 18 in the drawings, is connected at one side with the ground by means of the metal parts of the engine which are in electrical communication with the rails, and its opposite side is in constant connection with the trolley or contact shoe 19 of the contact device 14 as by means of a conductor 63.

35 The contact device has been shown in the drawings as composed of four pivoted arms, and a spring 20 by which the shoe at the upper ends of the arms is urged to yieldingly engage the overhead contact rails which for 40 the purpose of admitting the contact shoes to their lower surfaces are curved upwardly at their extremities.

The principal circuit controlling devices of 45 the system are two electro-magnetic switches one of which functions to cause a current flow through the field of the gate motor in one direction for its operation to lower the gate, while the other is provided to reverse the direction of the current flow for the 50 movement of the motor to reopen the gate.

55 The first described switch designated in its entirety by the numeral 21, has two contacts 22 and 23 to be engaged by contacts 33 and 34 on its armature 24 in one position and a third contact 25 engaged by a contact 35 on the armature in its other position.

60 The other switch indicated at 26, has but a single contact 27 which when the electric magnet is energized, is engaged by a contact 36 on the armature 28.

65 In addition to the main switches mentioned hereinabove, the system includes contact breakers 29 and 30 in connection with the gates, which are operated to open the circuits when the gate is opened or closed, for

the principal purpose of maintaining the closed position of the gate irrespective of the number of trains that pass the crossing at one time either one after another or from opposite directions.

70

The main circuits of the system are as follows: The two contact rails 15 at opposite sides of the crossing are connected by means of conductors 31 with one of the terminals of the magnet coil of the switch 21, the opposite end of which is connected with the ground at 32.

75

The contact 23 of the switch 21 is likewise connected with the contact rails 15 by a branch 37 of the conductor 31, the contact 22 of the same is connected with the ground 32, and the contact 25 connects with the contact rails 17 by conductors 38.

80

The contact 34 on the moving armature of the switch 21, is by means of a conductor 39 connected at one end of the field of the gate motor 9, the opposite end of the field being connected with the contact 33 of the armature by a conductor 40, and the contact 35 on the armature is connected with a terminal 85 of the magnet coil 26 by a conductor 41.

89

The other terminal of the coil 26 is connected with the ground by a conductor 43 and the conductor 38 connects the contact rails 17 with the conductor 40, when the contacts 25 and 35 are together.

95

The contact 27 of the switch 26 connects with the ground by a conductor 44, and the corresponding contact 36 on the armature 28, is connected with the side of the motor field opposite to that connected with the conductor 40 by means of a conductor 45.

100

A break in the conductor 31 is normally closed by the circuit breaker 29 of the gate, and a break in the conductor 41 is normally bridged by the circuit breaker 30.

105

These circuit breakers may be of any suitable construction and have been shown as consisting of a flexible contact blade connected at one side of the break in the circuit 110 and normally engaging with a fixed contact at the opposite side of the break, from which it is separated by the gate as it reaches its extreme position when closed or opened.

110

It is the object of the circuit-breakers to 115 open the circuit whose current flow moved the gate to either its open or closed position upon the gate reaching said positions, and thereby prevent further actuation of the gate in the same direction by other trains passing 120 the crossing during the period of operation caused by a train that approached the crossing in advance of the others.

115

Normally, when the system is not in operation, the switch 21 is in the condition shown 125 in Figure 2, the switch 26 in the condition illustrated in Figure 1, and the gate is in the open position in which the circuit breaker 30 has opened the gate-opening circuit.

125

A train approaching the crossing, engages 130

the contact 15 at the near side of the highway with its contact device 14, thereby energizing the electromagnet of the switch 21 as follows:

Beginning at the source 18 on the locomotive, the conductor 63, the contact shoe on the contact device 14, the contact rail 15, the conductor 31, in which is included the normally closed circuit breaker 29, the coil of the magnet and the ground 32.

The energization of the magnet causes its armature to move to the position illustrated in Figure 1 in which the circuit of the gate motor 9 is completed as follows:

Again commencing at the source 18 on the locomotive, the conductor 63, the contact shoe on the device 14, the overhead rail 15, the conductors 31 and 37, the contacts 23 and 34, the conductor 39, the motor field, the conductor 40, the contacts 33 and 22 and the ground 32.

The motor operating in clockwise rotation causes the gate to move to its closed position by means of the worm 10 and the worm gear 12, and the gate remains in this position while the train passes the crossing and after it has disengaged the contact rail 15.

As soon as the contact device on the locomotive disengages the contact rail 15, the coil of the switch 21 is deenergized and the armature 24 returns to its original position as shown in Figure 2.

The system remains inoperative and the gate is held in the closed position until the contact device on the train engages the contact rail 17 at the opposite side of the crossing when the magnet of the switch 26 is energized as follows:

Beginning at the source 18 on the locomotive, the conductor 63, the contact device 14, the overhead rail 17, the conductor 38, the contacts 25 and 35 of the switch 21, the conductor 41 closed in the circuit breaker 30, the magnet coil 26 and the conductor 43 connecting with the ground. The energization of the magnet 26 causes its armature 28 to bring the contact 36 in engagement with the contact 27, thereby closing the motor circuit as follows:

Commencing at the source 18, the conductor 63, the contact device 14, the contact rail 17, the conductor 38, the conductor 40, the motor field, the conductor 45, the contacts 36 and 27 and the conductors 44 and 43 leading to the ground.

The direction of rotation of the motor is thereby reversed and its movement in counter-clockwise direction causes the gate to be reopened.

It will be apparent that the relation of the two switches in their interconnected circuits, places the system in a condition which will cause the operation of the gate to move it from the position it occupies to its other position by the engagement of the contact

devices on the trains with the proper contact rails at either side of the crossing.

When the gate is being moved both circuits are closed in the circuit breakers, so that if during its opening movement after 70 a train has engaged one of the contact rails 17, another train moving either in the same direction or in the opposite direction, engages one of the contact rails 15, the movement of the gate will be immediately reversed so that the gate will remain closed as long as a train passes or approaches the crossing.

In order to apprise the engineer of a train approaching or passing the crossing, or of a train standing adjacent the crossing in engagement with one or another of the contact rails, of the position of the gate or gates at the crossing, a signaling appliance is installed in the cab of the engine. 85

For the purpose of operating the signaling appliances, auxiliary contact rails 47 and 48 are placed next to the contact rails 15 and 17, the contact device 14 on the engine is equipped with auxiliary contact shoes 49 and 50 adapted to engage the auxiliary rails and the gate is provided with two sets of contacts 51 and 52, the members of which engage one another when the gate is in either its wide open or its closed position. 95

In the cab of the locomotive designated by the numeral 53, are a red signal lamp 54 indicating the closed position of the gate and a green signal lamp 55 designating the open position of the gate and these lamps are connected in circuits controlled by the contact members on the gate, as follows:

The lamps 54 and 55 are connected with the source 18 by conductors 56 and 57, and with the contact shoes 50 and 49 respectively by conductors 58 and 59.

The contact members 57 and 52 on the gate are connected to the ground as at 60 and the corresponding stationary contacts 140 are connected with the auxiliary contact rails 48 and 47, respectively by conductors 61 and 62.

When the gate is in the closed position, and the contact device on the locomotive 115 engages the auxiliary contact rail 47 at the same time that it engages the contact rail 15, the circuit of the red signal lamp is closed as follows:

Beginning at the source 18, the conductor 56, the filament of the lamp 54, the conductor 58, the contact 50, the contact rail 47, the conductor 62, the contacts 52 on the gate, and the ground 60, and when the gate is open and the contact rail 48 next to the rail 17 is engaged by the trolley on the engine, the circuit of the green lamp is closed as follows:

Commencing again at the source 18, the conductor 57, the filament of the lamp 55, 130

the conductor 59, the contact shoe 49 on the contact device 14, the rail 48, the conductor 61, the contacts 51 on the gate, and the ground 60.

In order to enable the engineer of the train to move the train or engine as in switching, without disturbing the position of the gates at an adjacent crossing, a hand switch 64 is placed in the cab of the engine, to control the continuity of the conductor 63 between the generator 18 and the contact shoe or trolley on the pantograph 14.

The gates at the railway crossing may be provided with lamps or prismatic reflectors to apprise pedestrians or drivers of approaching vehicles of their closed position at night and an alarm of the type frequently used in connection with railway gates may be employed on the gates of the present invention to audibly give warning while they are moving to and from their closed position.

Inasmuch as indicatory devices of the above mentioned character are quite common and not an essential part of the invention, they have not been shown in the drawings.

Having thus described my invention, what I claim and desire to secure by Letters Patent is:

1. A system for the operation of railway gates comprising a gate, an electric motor operating the same, contact rails at opposite sides of a crossing protected by the gate, a train-carried source of electricity, a therewith connected contact device adapted to engage the contact rails at the crossing, circuits for the motor, connected to the contact rails, an electro-magnetic switch element controlling the circuits to effect the operation of the motor in opposite directions, and circuits for the switch element connected to the contact rails.

2. A system for the operation of railway gates comprising a gate, an electric motor operating the same, contact rails at opposite sides of a crossing protected by the gate, a train-carried source of electricity, a therewith connected contact device adapted to engage the contact rails at the crossing, circuits for the motor, connected to the contact rails, an electro-magnetic switch element controlling the circuits to effect the operation of the motor in opposite directions, circuits for the switch element connected to the contact rails, and means to open the last mentioned circuits by movement of the gate.

3. A system for the operation of railway gates comprising a gate, an electric motor operating the same, contact rails at opposite sides of a crossing protected by the gate, a train-carried source of electricity, a therewith connected contact device adapted to engage the contact rails at the crossing,

circuits for the motor, connected to the contact rails, an electro-magnetic switch element controlling the circuits to effect the operation of the motor in opposite directions, circuits for the switch element connected to the contact rails, and circuit breakers operated by movement of the gate to break the last mentioned circuits when the gate is in its closed or open positions.

4. A system for the operation of railway gates comprising a gate, an electric motor operating the same, a contact rail at a crossing protected by the gate, a train-carried source of electricity, a therewith connected contact device adapted to engage the contact rail at the crossing, a circuit for the motor, connected to the contact rail, an electro-magnetic switch element controlling the motor circuit, and a circuit for the switch element connected to the contact rail.

5. A system for the operation of railway gates comprising a gate, an electric motor operating the same, a contact rail at a crossing protected by the gate, a train-carried source of electricity, a therewith connected contact device adapted to engage the contact rail at the crossing, a circuit for the motor, connected to the contact rail, an electro-magnetic switch element controlling the motor circuit, a circuit for the switch element connected to the contact rail and means to open the last mentioned circuit by movement of the gate.

6. A system for the operation of railway gates comprising a gate, an electric motor operating the same, a contact rail at a crossing protected by the gate, a train-carried source of electricity, a therewith connected contact device adapted to engage the contact rail at the crossing, a circuit for the motor, connected to the contact rail, an electro-magnetic switch element controlling the motor circuit, a circuit for the switch element connected to the contact rail and a circuit breaker opening the last mentioned circuit by movement of the gate when the gate is closed.

7. A system for the operation of railway gates comprising a gate, an electric motor to operate the same, contact rails at opposite sides of a crossing protected by the gate, a train-carried source of electricity, a therewith connected contact device adapted to engage the contact rails at the crossing, circuits for the motor, connected to the contact rails, an electro-magnetic switch in a circuit connected to one of the contact rails, controlling a motor circuit to effect a current flow through the motor in one direction, and an electro-magnetic switch in a circuit connected to the other contact rail, controlling a motor circuit to effect a current flow through the motor in the opposite direction.

8. A system for the operation of railway gates comprising a gate, an electric motor

to operate the same, contact rails at opposite sides of a crossing protected by the gate, a train-carried source of electricity, a therewith connected contact device adapted to engage the contact rails at the crossing, circuits for the motor, connected to the contact rails, an electro-magnetic switch in a circuit connected to one of the contact rails, controlling a motor circuit to effect a current flow through the motor in one direction, and

closing a break in another motor circuit, in its deenergized condition, and an electro-magnetic switch in a circuit connected to the other contact rail, cooperating with the first switch in controlling the last mentioned motor circuit to effect a current flow through the motor in the opposite direction. ¹⁵

In testimony whereof, I have affixed my signature.

ARTHUR W. MUSSELMAN.
